COMBINED MOTOR AND SAIL BOAT

James H. McPartland, St. John, New
Brunswick, Canada

Application April 5, 1934, Serial No. 719,207

4 Claims. (Cl. 115—3)

This invention relates to boats and particularly to an improved combined motor and sail boat, the object being to provide a construction wherein the boat may be propelled through the use of either water or air propellers, or both, and through the use of a sail either alone or in connection with the other propellers.

Another object of the invention is to provide an improved boat wherein a single motor may be readily used to operate the water propeller or the air propeller for urging the boat forwardly or rearwardly.

An additional object of the invention is to provide in a motor boat sail means which may be used independently or in connection with the motor, the same means being readily mountable and demountable.

In the accompanying drawings—

Figure 1 is a top plan view of a boat disclosing an embodiment of the invention, the sail structure being eliminated;

Figure 2 is a longitudinal vertical sectional view through Figure 1 on the line 2—2;

Figure 3 is a plan view similar to Figure 1 but showing the sail in place with certain parts broken away and illustrating how the sail may be shifted;

Figure 4 is a fragmentary horizontal sectional view through the front part of the structure shown in Figure 3, illustrating the sail in lowered position;

Figure 5 is a sectional view through Figure 4 on the line 5—5;

Figure 6 is a fragmentary view on a scale similar to Figure 4 but showing a slightly modified structure wherein means have been provided for rolling the sail;

Figure 7 is an enlarged fragmentary horizontal sectional view through Figure 6 on the line 7—7.

Referring to the accompanying drawings by numerals, 1 indicates the body of a boat, which boat is provided with a motor 2 of any desired kind, a water propeller 3 also of any desired kind, and a pair of air propellers 4 and 5. As illustrated in the drawings there are provided three motive powers for propelling the boat, namely, the water propeller 3, the air propellers 4 and 5, and the sail propeller or structure 6. A power shaft 7 extends from the motor 2, said power shaft being connected to the propeller shaft 8 through a suitable clutch 9 whereby the shaft 8 may be connected and disconnected from the power shaft. When the parts are connected as shown in Figure 2, and the motor 2 is functioning, propeller 3 will be rotating. A large gear wheel 10

is splined on shaft 7 and is adapted to be slid into and out of mesh with the idler 11 through the action of the lever 12 which has one or more pins extending into the groove 14 formed on the sleeve 15 which is rigidly secured to or formed integral with the gear wheel 10, and which along with gear wheel 10 is splined on the shaft 7. When the parts are positioned as shown in Figure 2 and the motor 2 is functioning, the gear wheel 10 will be rotating and will rotate the idler 11 which in turn is continually in mesh with the pinion 16, whereby said pinion will be continually rotated and consequently the shaft to which it is secured, which shaft is carried by a suitable journal member 17, which in turn carries a beveled gear 18. A bracket 19 is carried by the sleeve 20 which surrounds the shaft 21 to which pinion 16 is secured. This bracket has ends 21 and 23 (Fig. 1) which loosely surround the transverse power shaft 24. A bevel pinion 25 is rigidly secured to shaft 24 and continually meshes with the gear wheel 18 so that when the gear wheel is rotating, shaft 24 will rotate and will rotate the auxiliary gears 26 and 27 which are rigidly secured thereto, said auxiliary gears continually meshing with the auxiliary pinions 28 and 29, which pinions are rigidly secured to the shafts 30 and 31. The respective propellers 4 and 5 are rigidly connected to the shafts 30 and 31. A pair of bracing bars 32 are connected to the sleeves 33 and 34 which are rotatably mounted on shafts 30 and 31 and held in position by the hubs of the propellers 4 and 5 and by the stops 35 and 36 which are rigidly secured to the shafts by suitable set screws. One of the cross bars 32 is provided with an ear 37 to which a cable 38 is secured, said cable being adapted to be looped over a hook 39 when the propellers 4 and 5 are swung upwardly as shown in dotted lines in Figure 2. This is done when it is desired to use propellers 4 and 5 to give a lifting action when the boat is traveling in rather shallow water. When the boat is traveling forwardly one of the bars 32 is resting on the support 40, which support is screwed into a threaded base 41. By rotating the support 40 the same may be raised and lowered to secure the desired elevation for the propellers.

It will be seen that the shafts 30 and 31 are held in place by a suitable U-shaped bracket 42 and 43, said brackets being rotatably mounted on shaft 24 and held in place by suitable stops. The stops or abutments are arranged on shafts 30 and 31 to prevent any longitudinal movement of these shafts with respect to these brackets though permitting a free rotary movement. By

5 this construction and arrangement the propellers may function as shown in Figure 2, or may be swung upwardly to the dotted position shown in the same figure, and still function. In addition the propellers may be swung over to rest on the rear support 40' and still permit the parts to function and power to be transmitted from motor 2 to the respective propellers so as to cause a reverse pulling action. When it is desired to move the boat a short distance to the rear or in a rearward direction, the clutch 9 is disconnected and the propellers swung over either when functioning or non-functioning, said movement continuing until the parts rest on the rear support 40'. When the propellers function in this position the boat will be pulled rearwardly. Sometimes this is done when it is desired to check the forward speed of the boat as the propellers may be quickly swung out without disconnecting them from the motor.

As shown in Figure 2 there is provided a plane 44 which is sometimes known as a fantail, said plane or fantail mounted at 45 to an enlargement 46 at the bottom of the boat. A controlling rod 47 is pivotally connected at 48 to the fantail 44 and extends upwardly to a point above the upper edge of the boat where a small apertured plate 49 is secured thereto. A screw member 50 having a pair of stops 51 and 52 extends through 30 this aperture and into the threaded extension 53 whereby when rotating wheel 54 the fantail 44 may be raised or lowered as desired. When the front of the boat begins to elevate as the speed increases the fantail is lowered and consequently 35 brings the boat on a more even keel, thus securing better results in view of the fact that the boat is lifted slightly so as not to extend into the water quite as far as it did heretofore. This reduces the resistance of the water and permits, 40 in a limited sense, a better planing action.

As shown more particularly in Figures 3 to 5, inclusive, there is provided a sail structure 6 which may be used if desired, or may be taken down and stored away on the boat when not in use. The sail structure 6 includes a hollow mast 55 which slips over the threaded base 41, as shown in Figure 4, and extends upwardly in the usual manner of masts. If desired bracing guy wires or other bracing members 56 and 57 may be used to reinforce the mast when in use. The top of the mast is provided with a pulley wheel 58 over which a cable 59 extends, said cable being adapted to be secured at any time to the post 60 and also to extend over the pulley 61. From post 60 the cable extends through or over pulley 61, pulley 58 and then downwardly until it is connected at 62 to the said sheet 63. As shown in Figures 4 and 5, the sail sheet is wrapped when not in use and is supported by the cable 59. Spars or bracing arms 65 and 66 are pivotally mounted on the mast 55 and may be positioned at right angles to the mast when the sail is in use, as shown in Figure 5, or may be swung to a parallel position when the mast is removed and stored in the boat. The sail at the lower end is secured to a boom 67 which is adapted to be rotated by hand wheels 68 and 69 whenever desired, or by some special mechanism as shown in Figures 6 and 7. This mechanism 70 consists of a corrugated roller 70 having a pinion 71 secured thereto, which pinion continually meshes with the idler 72, which in turn meshes with the pinion 73.

When the pinion 73 is rotated by the hand member 74 the train of gears just mentioned

will be caused to function and roller 70 will rotate through the action of friction to lower the sail and wrap it at the same time. It will be understood that the cable 59 is released gradually during this rolling operation. After the sail sheet has been rolled into place the sliding plate 75 is moved over to the position shown in Figure 4, unless it has previously been left in this place. After the sail has been rolled as shown in Figure 5 and it is desired to remove the mast, the same is merely lifted upwardly until it is disconnected from the base 41. The rolled sail 63 is then removed, plate 75 being slid out of the way during this operation. After the sail has been removed it is swung parallel to the mast and preferably lashed thereto, after which the mast, sail and associated parts are stored away. It will be understood that the members 65 and 66 are also swung to a parallel position with the mast before the mast is removed.

When the mast is in use the propellers 4 and 5 are swung to the rear as shown in Figure 3 and are usually disconnected from the power so that the propeller 3 and the sail will, act as a propelling means. The sail may be arranged as shown in Figure 3 and may be shifted by swinging the post so as to occupy a different position, as for instance, the position shown in Figure 3. Ropes 16 and 17 are used to hold the sail in the various positions in which it is placed. It will, therefore, be seen that when the sail is not in use it may be used either with or without the motor for propelling the boat, and when not in use either set of propellers may be used or both propellers may be used simultaneously to propel the boat forward or rearward. When propelling the boat rearwardly it will be necessary to reverse the propeller 3 which is done usually by reversing the engine 2. When the engine 2 is reversed and it is desired to use both of the air propellers as well as the water propeller, the air propellers are left in the position shown in Figure 2.

I claim:—

1 claim.
1. A boat of the character described, comprising a boat body, a water propeller exterior of the rear of the boat body, a pair of air propellers mounted substantially centrally of the boat body, said air propellers being mounted to swing around a horizontal axis, each of said air propellers having a driving shaft adapted to extend forwardly when in one position and rearwardly when in another position, a motor carried by the boat body, and a plurality of means for connecting said motor with the air propellers and the water propeller, said means being adapted to be adjusted to connect the air propellers and the water propeller at the same time to the engine and at another time to connect either the air propellers or the water propeller to the engine. 45 50 55 60

propellers or the water propeller to the engine. 60
2. A boat of the character described, including a boat body, a pair of air propellers, a shaft for each air propeller, a U-shaped bracket carried by each of said shafts at the ends opposite said air propellers, a shaft arranged transversely of the boat body, said brackets being loosely journaled on said last mentioned shaft, a pair of beveled gears for each of the air propeller shafts, one gear of each pair being rigidly secured to said transverse shaft, power means including a 70 motor for rotating said transverse shaft, and a manually actuated member for disconnecting said power means from said transverse shaft, said propellers and their operating shafts being swingable around said transverse shaft so that the air 75

- propellers may point towards the front, point upwardly and towards the rear and receive power in all these positions from said power means.
3. A boat of the character described, comprising a boat body, a water propeller carried by the boat body, an engine for driving said propeller, a pair of swingably mounted air propellers, means for transmitting power from said engine to the air propellers for causing the air propellers to rotate, a mast arranged adjacent the front of the boat body, a boom extending transversely of the mast an equal distance on each side thereof, means for normally supporting said boom, a sail having one end secured to said boom, the upper end adapted to be moved upwardly to the top of the mast, a cable connected to the upper end of said sail, means for guiding the cable over the top of the mast and downwardly to a point at the front of the boat body whereby said cable may be used for raising the sail at any time, and a plurality of manually actuated means for rotat-
- ing said boom and that part of the sail wound thereon to wind up the sail completely.
4. A boat of the character described, including a boat body, a removable mast arranged normally at the front of the boat body, a plurality of arms pivotally connected to said mast and when in one position arranged to extend transversely of the mast, a triangular shaped sail, a boom connected to the lower end of said sail, a cable connected to the upper end of said sail, means for actuating said cable over the top of the mast and downwardly towards the front of the boat body so that when the cable is pulled to the upper part said sail is pulled upwardly and in front of said arms, said mast being rotatable, and cables connected with the ends of said boom for manual actuation whereby the mast and sail may be shifted from one position to another for facing in the right direction with respect to the wind.

JAMES H. McPARTLAND. 20
